UNITED STATES PATENT OFFICE.

MARK W. HOUSE, OF CLEVELAND, OHIO.

IMPROVEMENT IN HARROWS.

Specification forming part of Letters Patent No. 29,885, dated September 4, 1860.

To all whom it may concern:

Be it known that I, MARK W. HOUSE, of Cleveland, in the county of Cuyahoga and State of Ohio, have invented a new and Improved Iron Harrow; and I do hereby declare that the following is a full and exact description thereof, reference being had to the accompanying drawings, which form a part of this specification.

Figure 1 is a perspective view of my said improved harrow minus a portion of its teeth $d d$; Fig. 2, a plan of said harrow minus the connecting center plates, $c c$; and the remaining drawings represent detached portions of said harrow.

In the construction of my said improved iron harrow I first take thin bars of wrought-iron of suitable length and bend them into nearly the form of triangular sections, the said sections $e g$ being of such a shape that they can be so united as to form the spokes and rim of a wheel. (Represented by Fig. 2 of the drawings.) I then securely combine the inner angles of said sections with each other by means of a pair of center plates, $c c$, and the necessary number of connecting-bolts, as represented in Fig. 1.

The draft-axle k , which may be of any desired size and shape, may be secured to the central portions of the center plates, $c c$, by

means of a flanged screw-shank and nut, or by any other method that may be preferred.

It will be perceived from the drawings that the rim portion g of each section of my improved harrow overlaps the adjoining section of the same a sufficient distance to enable each tooth d to be combined with two of said sections by means of a clamp, f , and a wedge or key, h , as represented in the drawings, which method of combining the harrow-teeth with the sections of the harrow-frame adds greatly to the stiffness and strength of the harrow, while at the same time it reduces the expense of its construction.

Should it be deemed preferable, the inner angles of the sections $e g$ of my improved harrow may be united to each other by means of a single center plate, c , and a series of staple-shaped bolts and screw-nuts.

What I claim as my invention, and desire to secure by Letters Patent, is—

Constructing a harrow of the respective parts represented in the accompanying drawings, when the said parts are combined with each other substantially in the manner herein set forth.

MARK W. HOUSE.
